(57) **CLAIM**

The ornamental design for an easel, as shown and described.

DESCRIPTION

FIG. 1 is a right-front perspective view showing the new easel design;

FIG. 2 is a top view thereof

FIG. 3 is a left-side view thereof (the right-side view is not shown but is a mirror image of the view shown in FIG. 3);
FIG. 4 is a front view thereof;

FIG. 5 is a rear view thereof;

FIG. 6 is a right-front perspective view thereof, shown with the upper two shelves removed and with the hooks shown in a different position.

FIG. 7 is a right-front perspective view thereof, shown with the upper shelf removed and with the hooks shown in a different position; and,

FIG. 8 is a right-front perspective view thereof, shown with the bottom and the upper shelves removed and with the hooks shown in a different position (the broken lines are for illustrative purposes only and form no part of the claimed design).

1 Claim, 8 Drawing Sheets
